DRYING DEVICE

Application filed November 4, 1930, Serial No. 493,448, and in Sweden April 12, 1929.

Application has been filed in Sweden, April 12, 1929.

When drying in canal drying devices in which the material to be dried passes through the canal on wagons or the like, and in which the drying air, by means of a number of ventilators, is brought to circulate in the transversal direction of the drying device, it is of importance that the quantity 10 of the drying air be as large as possible because the drying when using large quantities of air takes places more rapidly and more uniformly. Of late endeavors have therefore been made to attain larger quantities 15 of circulation air than hitherto. This has, however, resulted in a decided increase in the power consumption.

Endeavors have been made to reduce the power consumption required for maintaining a uniform drying. A step in such a direction has been taken by mounting the ventilator wheels necessary for the air circulation on a shaft running along the drying device. Thus, the driving of all the ventilators can take place from a single motor, steam-turbine or the like without losses in transmissions, belts or machinery. Though certain savings in power are gained solely through this device against older devices, 30 the power consumption can be still more reduced by the present invention.

The reason for the irregular drying lies mainly in the fact that the capacity of the drying air to take up moistness is reduced 35 more and more when passing through the material to be dried. If the direction of the air be reversed with certain equal intervals, while the material will, at a certain point, be subjected to air having a smaller drying 40 capacity, this is compensated for by the fact that the material in the intervals is treated with air having a larger drying capacity. Thus, the quantity of the circulation air may be reduced resulting in savings in power.

Attempts have hitherto been made to solve the question of reversal of the air direction, by mounting propeller ventilators or the like on a common shaft, said ventilators supplying air in one direction when rotating 50 in one direction, and supplying air in the

opposite direction when rotating in the other direction. It is, however, known that ventilators which must supply air in opposite directions only by reversing the direction of rotation do not operate efficiently. A far better result is obtained if the ventilator wheels are constructed for rotation only in one direction. According to tests made in a trial plant of the latter kind the savings in power amount to about 50%. 55 60

The reverse of the direction of circulation is carried out in the present invention by simultaneous reversal of the dampers or valves appertaining to the ventilator housings. All the dampers being compulsorily 65 connected to each other, the reversal can take place simultaneously by means of a single controlling means. In drying devices of the kind in question it is further of importance that the air to be exhausted leave the drying device saturated with moisture as fully as possible, without regard to the direction of the air circulation within the drying device. For this purpose the drying device is provided with a special 70 exhaust ventilator working independently of the circulation ventilators. To this special exhaust ventilator there are connected one or more suction conduits located in the vicinity of the heat batteries, preferably directly above said batteries. The air arriving in the suction conduit through the valves of the same has always, independently of the direction of circulation 75 within the drying device, passed the material to be dried, and is, thus, well saturated with moisture. 80 85

Thus, the present invention relates to a new combination of devices known per se, by which a considerably improved technical 90 effect is obtained.

An embodiment of the invention is shown in the accompanying drawings. Fig. 1 is a longitudinal section of the drying device, Fig. 2 is a horizontal section of the same drying device, and Fig. 3 is a cross section along the line III—III of Fig. 2. Fig. 4 is a detail vertical sectional view on line IV—IV of Fig. 3. Fig. 5 is a fragmentary 95 horizontal sectional view on line V—V of 100

Fig. 3. Fig. 6 is a detail transverse sectional view on line VI—VI of Fig. 1.

1 and 2 are drying canals in which the material to be dried is placed on trucks. 5 3 are heat batteries for heating the circulation air. 4 are ventilator housings and 5 ventilator wheels. The longitudinal shaft is indicated by 6, and the motor for driving the same by 7. 8 and 9 indicate reverse 10 dampers. 10 is the exhaust ventilator which through the suction conduits 12 and 11 communicate with the drying chamber and through the conduit 13 discharge into the free air. 14 are intake openings for the 15 ventilation air. 15 are valves on the suction conduit 12.

The plant operates in the following manner: When the motor 7 rotates the shaft 6, all ventilator wheels 5 rotate in their ventilator housings 4. The air is thereby driven from the ventilator housings 4 through the vertical passages 16 to the drying canal 2. The air having passed through the material to be dried in this canal, passes and contacts 25 with the heat batteries 3. From there the air goes further to the drying canal 1, flows through the material to be dried in this canal and returns through the passages 17 to the ventilator housings 4.

30 While the circulation continues in this manner, the material to be dried in the canal 1 is subjected to air having a larger drying capacity than the material in the canal 2. When this has continued for a while, the 35 dampers 8—9 are turned 180°. The air current now changes its direction through the drying device. Thus, the material to be dried in the canal 2 will be subjected to air having a larger drying capacity than the 40 material in the canal 1. If the dampers are reversed with equal intervals, the material to be dried in the canal 1 will dry as rapidly as the material to be dried in the canal 2, and vice versa. For controlling and actuating 45 the dampers 8 and 9, the following device shown more particularly in Fig. 5 may be used. Each damper shaft 25 is provided with a toothed segment 26 meshing with a worm 27 and this worm is fixed on 50 a shaft 28 extending throughout the length of the dryer. Although, only one of the dampers 8 and one of the dampers 9 are shown in Fig. 5, together with their gearing, it is to be understood that the arrangement 55 is the same for each of the dampers required, and that any desired number of the latter may be used. The shafts 28 are connected for synchronous rotation by a chain 29 and sprockets 30, and a hand wheel 31 having a 60 handle 32, is provided on one of said shafts.

The quantity of air which shall be in circulation becomes about half as much as would have been the case if no reverse of the direction of the air had taken place.

65 Due to the ventilators always rotating in

the same direction, paddles or the like in the ventilator wheels may be constructed more advantageously and thus the effect will be considerably improved.

The ventilation air enters through the 70 openings 14, and a corresponding quantity of air which is exhausted through the valves 15, passes through the conduits 12 and 11 to the exhaust ventilator 10, and is exhausted from there into the free air through the 75 conduit 13.

The heat batteries 3 are mounted in a tight partition 18 which runs between the floor and the exhaust conduit 12 along the 80 whole drying device. Besides the passage for the air, which is formed by the batteries, holes 19 are formed in the wall 18 adjacent the suction openings 15, and further, an opening 19a is formed in the same wall, near the end of the conduit 12 (see Fig. 1). The 85 object of this is that only air which has passed the material to be dried, but not yet the heat batteries, shall be sucked into the suction conduit 12.

In order that the air from the heat batteries shall be distributed through the whole 90 mass of the material to be dried, apertured walls 20 are located on each side of the row of batteries, said walls preferably having 95 their apertures in the form of slots 21 uniformly distributed along the whole length of the drying device.

The drying device described above should 100 only be considered as one embodiment of the invention. Other embodiments may be provided without departing from the principle 105 of the invention. The number of the canals may, for instance, be varied, further the drying canals and the batteries may be placed at the top, and the ventilator housings below instead of vice versa.

We claim:—

1. In a drier, a canal for the material to be dried, a shaft extending longitudinally of and disposed externally of said tunnel, means for driving said shaft in one direction, a plurality of fans secured on said shaft and spaced apart longitudinally thereof, individual housing for said fans, one row of passages disposed transversely with respect to the canal and extending from one side of said canal to said fan housings, a second row of passages transverse with respect to the canal and extending from the opposite side of said canal to said fan housings, and valve means for placing either row of said passages in communication with the intake sides of the fans and the other row in communication with the discharge sides of said fans, allowing expeditious reversal of the fan-created air currents without reversing the fans.

2. In a drier, two canals for the material to be dried, said canals having substantially horizontal top and bottom walls, means

for admitting fresh air to said canals, and air exhausting suction conduit extending longitudinally between said canals and having longitudinally spaced exhaust air inlets, said suction conduit being adjacent one of said horizontal longitudinal walls, longitudinally disposed partition means between the two canals, said partition means extending from said suction conduit to the other 10 of said horizontal walls and embodying air heating means, and means for forcing air alternately in opposite directions across said canals and through said heating means.

3. In a drier, two canals for the material to be dried, said canals having substantially horizontal top and bottom walls, means for admitting fresh air to said canals, an air exhausting suction conduit extending longitudinally between said canals and having 20 longitudinally spaced exhaust air inlets, said suction conduit being adjacent one of said horizontal longitudinal walls, longitudinally disposed partition means between the two canals, said partition means extending from said suction conduit to the other of said horizontal walls and embodying air heating means, means for forcing air alternately in opposite directions across said canals and through said heating means, and vertical 30 longitudinal apertured air distributing walls spaced outwardly from opposite sides of said suction conduit and partition means, said air distributing walls having openings adjacent said exhaust air inlets of said suction conduit.

4. In a drier, an elongated enclosure having fresh air admission means, said enclosure being divided by a horizontal partition into a canal compartment and a fan housing compartment, an air exhausting suction conduit extending centrally under said horizontal partition and having longitudinally spaced exhaust air inlets, a vertical longitudinal partition extending from the lower 45 side of said suction conduit to the bottom of said canal compartment and dividing the latter into two drying canals, said vertical partition having longitudinally spaced openings and air heating means in said openings, 50 vertical longitudinal air distributing walls spaced outwardly from opposite sides of said suction conduit and said vertical partition, said walls having exhaust air openings adjacent said exhaust air inlets of said conduit, longitudinally spaced fan housings in said fan housing compartment, fans in said housings respectively, a row of vertical air passages from said fan housing to the outer side of one of said canals, a second row of 55 vertical air passages from said fan housings to the outer side of the other canal, means for driving all of said fans in the same direction, and means for placing either of said rows of air passages in communication 60 with the admission sides of said fans and the

other row of air passages in communication with the discharge sides of said fans.

In witness whereof we have hereunto signed our names.

JOHAN GUSTAF OLSSON.
